United States Patent Office

Des. 234,109
Patented Jan. 21, 1975

234,109

GOBLET OR SIMILAR ARTICLE

Walter B. Achenbach, Toledo, Ohio, assignor to Owens-Illinois, Inc., Toledo, Ohio

Filed July 30, 1973, Ser. No. 384,131

Term of patent 14 years

Int. Cl. D7—01

U.S. Cl. D7—12

FIG. 5

FIG. 1

FIG. 2

FIG. 3

FIG. 4

FIG. 6

FIG. 1 is a front elevational view of a goblet or similar article showing my new design;

FIG. 2 is an elevational view of the right side thereof;

FIG. 3 is an elevational view of the back side thereof;

FIG. 4 is an elevational view of the left side thereof;

FIG. 5 is a top plan view thereof;

FIG. 6 is a bottom view thereof.

I claim:

The ornamental design for a goblet or similar article, as shown and described.
